UNITED STATES PATENT OFFICE.

CHARLES OSCAR ULLIN, OF KENDALLVILLE, INDIANA, ASSIGNOR TO McCRAY
REFRIGERATOR COMPANY, OF KENDALLVILLE, INDIANA, A CORPORATION OF INDIANA.

DESIGN FOR A CANDY-REFRIGERATOR.

47,441.

Specification for Design.

Patented June 8, 1915.

Application filed February 18, 1915. Serial No. 9,190. Term of patent 7 years.

To all whom it may concern:

Be it known that I, CHARLES OSCAR ULLIN, a citizen of the United States, residing in Kendallville, in the county of Noble, State of Indiana, have invented a new, original, and ornamental Design for a Candy-Refrigerator, of which the following is a specification, reference being had to the accompanying drawing, forming a part thereof.

The figure is a perspective view of a candy refrigerator.

I claim:

The ornamental design for a candy refrigerator as shown.

CHARLES OSCAR ULLIN.
